Ezra D. Sargent

UNITED STATES PATENT OFFICE.

EZRA D. SARGENT, OF INDIANAPOLIS, INDIANA.

SEAT AND COUCH FOR RAILROAD-CARS.

Specification of Letters Patent No. 25,049, dated August 9, 1859.

To all whom it may concern:

Be it known that I, EZRA D. SARGENT, of the city of Indianapolis, county of Marion, and State of Indiana, have invented a new 5 and useful Improvement in the Construction and Arrangement of Passenger - Cars for Railroads; and I do hereby declare that the following is a full and exact description of the same—to wit:

10 The nature of my invention consists in providing a simple and economical form and arrangement of seats and their backs which can be metamorphosed into night couches— (from day seats) by a process as plain and 15 simple as it is novel—and not attained in any other similar device.

To enable others, skilled in the art, to make and use my invention, I will now proceed to describe the same—as to construction 20 and operation.

Figure 1, is a longitudinal sectional view of a portion of a passenger car; Fig. 2, is the rear view of a back cushion belonging to one of my day seats—showing also, the connecting bolt and the loop through which said bolt works; Fig. 3, is a longitudinal elevation of the partition between the seats,—together with an edge view of the seat backs—and the pillows K, K, between.

30 A, B, and C, are panels, or spaces, between the windows.

D, is the section of one half—or one side—of a car, showing H—the front of seat, with J—the cushion placed under the same upon 35 the brackets d, d.

L, L, M, M, N, N, and O, are an edge view of the seat backs—(from the aisle).

P, P, P, P, are partitions between seats.

E, E, F, F, H, H, the ends of seat cushions.

40 T, T, T, T, are berth or couch curtains, suspended on R, R, &c., the curtain rods.

G—as seen in the drawing here—represents one of the spare cushions—(which occupies the place indicated by “J” at the 45 right hand end of Fig. 1, when not in use) but, as here represented it serves as a connecting link between the wall end of two seats—and so, constitutes a “lounge” or nurse couch, for the convenience of invalids 50 or families.

Now, the points of “novelty” of my invention over other inventions of a similar kind, consist in, 1st. While all others have two or more surplus cushions, (which are entirely worthless in the day time) mine has but one. 2nd. While all others are so con-

structed that the seat cushions have invariably to be moved in metamorphosing the day into night, or the night into day accommodations—mine on the contrary are changed 60 and adjusted in an incredibly short space of time—and that too without the slightest disturbance of any of the permanent fixtures. 3d. Since I have but one surplus cushion and vary my general device but little from that 65 of an ordinary passenger car—having nothing redundant, and all the parts useful, no one can reasonably question the vast stride I have taken in the road of rigid economy when my invention is brought in contrast 70 with others. 4th. In the arrangement of my cushions (when they are used for sleeping purposes) I avoid breaking joints under those parts of the sleeper’s body where the bearings are—hence, I make an easy couch— 75 an item too much neglected in other similar inventions.

The mode of operation—or, the manner of converting my day seats into night couches, is simple—and naturally suggested by the 80 very device itself; viz: The bolt V being withdrawn the backs are taken down from the position shown in the panel space C,—the hooks in the ends of the backs are placed in ledges, or protruding eyelets, in the partitions. The pillows K, K, are properly adjusted above and below. Then cushions J, &c. are placed between the seat cushions proper—in the front—and the cushions G, &c., are placed next the side, or wall of the 90 car, and the curtains being arranged—all is now ready for use—as a night, or sleeping couch. To reduce them back to the day arrangement, this process is reversed.

I disclaim any originality in the conversion of day seats into night couches, as I am aware that various devices are in use—of this nature;—but

What I do claim, and desire to secure by the grant of Letters Patent, is—

1. The side lounge G, or nurse couch, constructed and arranged as, and for the purpose set forth;—and

2. Its combination with the backs —a— L, M,—seats F, G, H, J,—partitions P,—brackets Z, and stops —V,—all arranged, constructed, and operated substantially as set forth in the foregoing specification.

EZRA D. SARGENT.
